UNITED STATES PATENT OFFICE.

WILLIAM CRYE, OF WALLA WALLA, WASHINGTON TERRITORY.

MIDDLENS-PURIFIER.

SPECIFICATION forming part of Letters Patent No. 247,018, dated September 13, 1881.

Application filed May 24, 1880. (No model.)

To all whom it may concern:

Be it known that I, WILLIAM CRYE, of Walla Walla, in the county of Walla Walla and Territory of Washington, have invented 5 a new and useful Improvement in Middlens-Purifiers, of which the following is a specification.

The invention relates to middlens-purifiers used in the process of manufacturing flour; 10 and it consists in certain novel features, hereinafter described.

The construction and operation will be particularly described hereinafter with reference to the accompanying drawings, wherein—

15 Figure 1 is a vertical longitudinal section of a middlens-purifier constructed in accordance with my invention. Fig. 2 is a vertical transverse section on line $x-x$ of Fig. 1. Fig. 3 is a sectional detail view, representing the 20 endless screw and nut; and Fig. 4 is a face view of the nut.

The same letters of reference indicate the same or corresponding parts.

A is the casing of the machine, supported 25 on legs, provided with the feed-hopper a and feed-roller b at the top, and delivery-hopper c and conveyer d at the under side, as usual.

B is a suction-fan, placed at one end of the machine, connected by spout e with air-chamber f beneath hopper a , and communicating 30 also with the air-chamber g , that is above the screen h . The air-chamber f is formed by the sides and end of casing A and the inclined board i , which extends from the end of spout 35 e to near the upper end of the screen h .

In the chamber f , above board i , there are fitted inclined boards $k k'$, the upper one of which receives the material from feed-roller b and delivers it upon the next board, the material being thus passed down to board i , from 40 which it runs to the screen. The boards $k k'$ thus form a number of separate passages for the air drawn in at the front openings, l , so that the action of the blast upon the material 45 is rendered uniform and effective. $m m$ are slides fitted at the openings l , for regulating the inlet of air.

In the air-chamber g is a perforated partition, n , that divides the said chamber. The

air is drawn from said chamber by the passage p , leading to fan B , and by the perforations in partition n . These perforations are made larger toward the side of the machine, so that the draft through the screen will be equally as strong at the sides as at the middle portion. 50 The opening p is fitted with a slide, o , for use in regulating the blast.

Beneath the screen h a frame, r , carrying brushes r' , is fitted in suitable slideways, so that it may be reciprocated and the screen 60 kept clean by the action of the brushes. Beneath the frame, in suitable bearings, is fitted a screw, s , cut with a double or endless thread, and fitted with a nut, t , that connects by a rod with the brush-frame r , so that by revolution of the screw the frame r is moved. The nut t , as shown in Figs. 3 and 4, is formed 65 with a right and a left hand thread, and is fitted for being tilted by contact with fixed pins at the end of its traverse to disengage 70 one thread and engage the other, so that the nut will be reciprocated.

The screw s is to be rotated by suitable connections from the main driving-pulley, and the screen h is to be vibrated by an eccentric or 75 crank in any desired manner.

In operation the material fed by hopper a is spread evenly by the feed-roller, and by boards $k k'$ presented to the air in the best position for effective operation of the blast. The greater 80 part of the dust and other impurities will be drawn out through the spout e . The partition n above the screen serves to equalize the action of the blast on the material while it is being screened, and the remaining impurities will be thoroughly removed. 85

Having thus described my invention, I claim as new and desire to secure by Letters Patent—

The combination of the double-threaded rod s , the double-threaded nut x , suitable means 90 for tilting said nut alternately in opposite directions at the ends of its course, and the brush-frame $r r'$, substantially as and for the purpose specified.

WILLIAM CRYE.
